UNITED STATES PATENT OFFICE.

FELIX ZYH, OF CHICAGO, ILLINOIS.

CHAFING IRON.

Application filed April 14, 1922. Serial No. 552,732.

To all whom it may concern:

Be it known that I, FELIX ZYH, a citizen of the Republic of Poland, residing at Chicago, in the county of Cook and State of Illinois, have invented new and useful Improvements in Chafing Irons, of which the following is a specification.

This invention relates to a chafing iron particularly designed for use in connection with railway engines and their tenders or water tanks, and an object of the invention is to provide a chafing iron structure which will have a revolving motion and will materially reduce the number of derailings of engines or tenders, eliminating the work necessary in replacing, and repairing the rolling stock, and will also materially reduce the work of replacing, adjusting and repairing the chafing plates and shortening the draw bar such as now used.

Another object of this invention is to provide a chafing iron structure as specified which will permit the engine or tender to move vertically or laterally to prevent slackening of the connection, and materially eliminate the jerking in pushing or switching across over curved or weak tracks, and one which will not require extensive alterations in the present construction for applying it. Other objects of the invention will appear in the following detailed description taken in connection with the accompanying drawings wherein:

Fig. 1 is a top plan of the improved chafing iron showing it applied.

Fig. 2 is a vertical longitudinal section through the improved chafing iron showing it applied.

Fig. 3 is a fragmentary vertical transverse section through the improved chafing iron structure.

Fig. 4 is a perspective view of the tender carried section of the chafing iron.

Fig. 5 is a perspective view of the intermediate section of the chafing iron.

Fig. 6 is a detail view of a part of the engine carried section.

Fig. 7 is a detail section on the line 7—7 of Fig. 3.

Referring more particularly to the drawings, the improved chafing iron structure comprises a tender or tank carried member 1 which is attached to the tender or tank A in any suitable manner and has a flange 2 which overhangs a portion of the tender, as clearly shown in Figs. 1 and 2 of the draw-

ings. The tender carried section 1 has a forwardly extending centrally disposed portion 3 the forward surface of which is concavely curved horizontally as clearly shown at 4 in the drawings, and it receives the convexly curved surface 5 of the intermediate section or member 6, the curvature of which conforms to the concave curvature of the projection 3. Vertical flanges 7 are formed at the ends of the convexly curved surface 5 for engagement with the ends of the projection 3 for limiting the relative rocking movement of the sections 1 and 6. A plate 8 is formed upon the upper end of the intermediate section 6 and it is provided with an opening 9 adapted to receive a pin 10 which pin extends into an oval shaped recess 11 formed in the upper end of the section 1.

The forward surface of the section 6 is flat, as shown at 12, and vertical flanges 13 extend along each end of the flat surface for preventing lateral disconnection between the section 6 and the engine carried section 14. The member or section 14 is provided with a pair of rectangular lugs 15 on the concave surface 3, which seat in suitable recesses 16 formed in the convex surface of the section 6. The recesses 16 are considerably longer than the lugs 15 so as to permit relative lateral rocking movement of the sections 1 and 6.

The engine carried section 14 includes an abutting plate 18 which abuts the flat forward surface 12 of the intermediate section 6 being prevented from lateral movement relative to the intermediate section by the vertical flanges 13. The abutment plate 18 has a rectangular projection 19 formed on its forward surface the rear surface of which is recessed as shown at 20 in Fig. 6 of the drawings, the said recessed surface inclines transversely, decreasing in depth from one edge of the rectangular projection 19 to the other for receiving the adjusting connecting wedge 21. The lower edge of the recess 20 is cut in as shown at 22 to receive the lower edge of the wedge 21 for locking the abutment plate 18 to the section 23 which is permanently carried by the engine as indicated at B. The wedge 21 is provided with a plurality of ratchet teeth 24 on its upper edge with which a pawl 25 cooperates to prevent reseating movement of the wedge, and the wedge is urged inwardly against the inclined surface 20 by a spiral spring 26 coiled about a bolt or rod 27. The rod or bolt 27

projects through an upstanding ear 28 carried by the wedge 21 and it has a suitable member 29 thereon to prevent relative movement of the bolt and wedge. The tension of the spring 26 is regulated by an adjusting or tensioning sleeve 30 which is threaded upon the bolt 27 and slides through a suitable guide 31 carried by the member 23. The bolt 27 also extends through a guide 32 carried by the member 23. The tendency of the wedge 21, is to move the abutment plate 18 rearwardly and maintain it in snug fitting engagement with the flat surface 12 of the intermediate section 6, at all times but to permit vertical movement of the abutment plate relative to the intermediate section 6, such as is necessary at times during the travel of a locomotive over uneven tracks. Relative lateral movement of the engine B 20 and its tender or tank A is permitted by the connection of the sections 6 and 18.

It is, of course, to be understood that the invention may be constructed in other manners and the parts associated in different relations and, therefore, I do not desire to be limited in any manner except as set forth in the claims hereunto appended.

Having thus described my invention what I claim is:

- 30 1. In a chafing iron for railroad rolling stock, a tender carried section provided with a concave forward surface, an intermediate section provided with a convex surface engaging said concave surface, said surfaces being curved on a horizontal arc and mounted for limited lateral rocking movement relative to each other, said intermediate member provided with a flat forward side, and an engine carried abutment plate abutting said flat side and adapted to move vertically relative to the intermediate member.
- 35 2. In a chafing iron for railroad rolling stock, a tender carried section provided with a concave forward surface, an intermediate section provided with a convex surface engaging said concave surface, said surfaces being curved on a horizontal arc and mounted for limited lateral rocking movement relative to each other, said intermediate member provided with a flat forward side,
- 40 3. In a chafing iron for railroad rolling stock, a tender carried section provided with a concave forward surface, an intermediate section provided with a convex surface engaging said concave surface, said surfaces being curved on a horizontal arc and mounted for limited lateral rocking movement relative to each other, said intermediate member provided with a flat forward side, and an engine carried abutment plate abutting said flat side and adapted to move vertically relative to the intermediate member.
- 45 4. In a chafing iron for railroad rolling stock, a tender carried section provided with a concave forward surface, an intermediate section provided with a convex surface engaging said concave surface, said surfaces being curved on a horizontal arc and mounted for limited lateral rocking movement relative to each other, said intermediate member provided with a flat forward side,
- 50 5. In a chafing iron for railroad rolling stock, a tender carried section provided with a concave forward surface, an intermediate section provided with a convex surface engaging said concave surface, said surfaces being curved on a horizontal arc and mounted for limited lateral rocking movement relative to each other, said intermediate member provided with a flat forward side, and an engine carried abutment plate abutting said flat side and adapted to move vertically relative to the intermediate member.
- 55 6. In a chafing iron for railroad rolling stock, a tender carried section provided with a concave forward surface, an intermediate section provided with a convex surface engaging said concave surface, said surfaces being curved on a horizontal arc and mounted for limited lateral rocking movement relative to each other, said intermediate member provided with a flat forward side, and an engine carried abutment plate abutting said flat side and adapted to move vertically relative to the intermediate member.

lateral movement of the tender and intermediate sections.

3. In a chafing iron for railroad rolling stock, a tender carried section provided with a concave forward surface, an intermediate section provided with a convex surface engaging said concave surface, said surfaces being curved on a horizontal arc and mounted for limited lateral rocking movement relative to each other, said intermediate member provided with a flat forward side, an engine carried abutment plate abutting said flat side and adapted to move vertically relative to the intermediate member, said tender carried member provided with a pair of lugs projecting outwardly from its concave surface, said intermediate member provided with elongated recesses for receiving said lugs and for limiting relative lateral movement of the tender and intermediate sections, a plate carried by the upper end of said intermediate section, an overhanging portion upon the upper end of said tender section, said tender carried section provided with an elongated recess, and a pin carried by said plate and engaging said recess.

4. In a chafing iron for railroad rolling stock, a tender carried section provided with a concave forward surface, an intermediate section provided with a convex surface engaging said concave surface, said surfaces being curved on a horizontal arc and mounted for limited lateral rocking movement relative to each other, said intermediate member provided with a flat forward side, an engine carried abutment plate abutting said flat side and adapted to move vertically relative to the intermediate member, said tender carried member provided with a pair of lugs projecting outwardly from its concave surface, said intermediate member provided with elongated recesses for receiving said lugs and for limiting relative lateral movement of the tender and intermediate sections, a plate carried by the upper end of said intermediate section, an overhanging portion upon the upper end of said tender section, said tender carried section provided with an elongated recess, and a pin carried by said plate and engaging said recess, a wedge member engaging said abutment plate for urging it into binding abutment with said intermediate member, a spring urging said wedge in abutment plate urging position, and means for regulating the tension of said spring.

In testimony whereof I affix my signature.
FELIX ZYH.
